Letters Patent No 490 Dated Aug 17th 1852

The schedule referred to in these Letters Patent and making part of the same

Be it known that I, John S. Perry of the City of Albany, State of New York, have produced an ornamental Design for a Cooking Stove (which I have named the May Flower) and I do hereby declare that the annexed drawings are accurate & full delineations of the ornamented parts with their several ornaments, the side plate with doors not represented being symmetrical similar to that represented, and where portions of plates and of the sections of the plates only are shewn the portions not shewn being similar to & symmetrical with those shewn.

What I claim as my production & desirous to secure by Letters Patent, is the combination & arrangement of ornamental figures & forms, represented in the accompanying drawings, forming together an ornamental design for a Cooking Stove.
